US00D999550S

(12) **United States Design Patent** (10) **Patent No.:** **US D999,550 S**
Wang et al. (45) **Date of Patent:** **** Sep. 26, 2023**

(54) **ANGLE ADJUSTING APPARATUS**

- (71) **Applicant:** **SHANGHAI IMILAB TECHNOLOGY CO., LTD.**, Shanghai (CN)
- (72) **Inventors:** **Yajun Wang**, Shanghai (CN); **Maofeng Kao**, Shanghai (CN); **Kaining Li**, Shanghai (CN)
- (73) **Assignee:** **SHANGHAI IMILAB TECHNOLOGY CO., LTD.**, Shanghai (CN)

(***) **Term:** **15 Years**(21) **Appl. No.:** **29/770,924**(22) **Filed:** **Feb. 17, 2021**(51) **LOC (14) Cl.** **08-11**(52) **U.S. Cl.**USPC ..... **D8/373**; D10/121(58) **Field of Classification Search**

(57)

CLAIM

The ornamental design for an angle adjusting apparatus, as shown and described.

DESCRIPTION

FIG. 1 is a rear view of the design;
FIG. 2 is a left view of the design;
FIG. 3 is a right view of the design;
FIG. 4 is a front view of the design;
FIG. 5 is a top view of the design;
FIG. 6 is a bottom view of the design; and,
FIG. 7 is a perspective view of the design.

1 Claim, 7 Drawing Sheets(56)
